US0D1088698S

(12) **United States Design Patent** (10) **Patent No.:** **US D1,088,698 S**
(45) **Date of Patent:** **** Aug. 19, 2025**

(54) **COUNTERTOP COOKING APPLIANCE**

(71) Applicant: **WHIRLPOOL CORPORATION**,
Benton Harbor, MI (US)

(72) Inventors: **Megan Cheryl Dado**, Benton Harbor, MI (US); **Edward James Haney**, Baroda, MI (US); **John W. McConnell**, St. Joseph, MI (US); **Mansour Ourasanah**, Chicago, IL (US); **Ryan James Rutter**, St. Joseph, MI (US); **Lesley J. Frakes**, Coloma, MI (US)

(73) Assignee: **WHIRLPOOL CORPORATION**,
Benton Harbor, MI (US)

(**) Term: **15 Years**

(21) Appl. No.: **29/978,906**

(22) Filed: **Dec. 16, 2024**

(57) **CLAIM**

The ornamental design for a countertop cooking appliance as shown and described.

DESCRIPTION

FIG. 1 is a perspective view of a countertop cooking appliance according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the article shown in broken line form no part of the claimed design.

Diagonal shading is used to represent features that are transparent or reflective.

1 Claim, 7 Drawing Sheets

Related U.S. Application Data

a continuation of application No. 29/915,889, filed on Nov. 6, 2023, now Pat. No. Des. 1,038,679, which is a continuation of application No. 29/827,142, filed on Feb. 17, 2022, now Pat. No. Des. 1,011,821.
